UNITED STATES PATENT OFFICE.

GRACE R. STRONG, OF STAPLETON, NEW YORK.

GAME DEVICE.

1,365,863.

Specification of Letters Patent. Patented Jan. 18, 1921.

Application filed October 20, 1919. Serial No. 331,809.

To all whom it may concern:

Be it known that I, GRACE R. STRONG, a citizen of the United States, residing at Stapleton, Staten Island, in the county of Richmond and State of New York, have invented certain new and useful Improvements in Game Devices; and I do declare the following to be a full, clear, and exact description of the invention, such as will enable others skilled in the art to which it appertains to make and use the same.

This invention relates to game devices.

An object of the invention is to provide an improved parlor game-board on which an exceedingly interesting game may be played by two or more persons.

Another object is to provide a device of this character which tends to increase public interest in farm life, thereby promoting the production of farm products.

Other objects and advantages may become apparent to persons who read the following details of description in connection with the accompanying drawings, in which:—

Figure 1 is a top plan view of a game-board made in accordance with the present invention.

Fig. 2 is a perspective view illustrating a form of inclosure or pen including separately movable fence sections or pickets seated in slots in the board.

Fig. 3 is a vertical sectional view, the section being taken substantially along the line 3—3 of Fig. 1.

Fig. 4 is a perspective view illustrating a storage sheath and a plurality of the pickets in the sheath.

Fig. 5 is a perspective view illustrating a stack of representations of animals, which constitute game counting members.

Referring to the drawings in detail, in which similar reference characters correspond with similar parts throughout the several views, the game device comprises a game board which is generally designated by the numeral 6, a plurality of pickets or fence sections 7, gates 8 and counting members 9.

Referring more particularly to Fig. 3, it will be seen that the game board 6 may constitute the lid of a flat box, the remaining portion of the box being indicated at 6', and the fence sections and counting members may be kept in the box when the game is not being played. However, this invention is not limited to the box construction, and any appropriate means may be employed for sup-

porting the lower ends of the pickets 7 where they extend through apertures 10 in the box-top or game-board. There are four endless series of pickets or fence sections 7 and 8 60 illustrated in Fig. 1, this embodiment of the invention being designed for two or four persons playing the game which may be entitled "Getting the goats," "Fencing the goats," or a somewhat similar name, depending on whether goats are represented by the members 9 or whether some other animal or living creature is represented thereby, it being understood that this invention is not limited to the representation of goats, although goats have been chosen for the purpose of illustrating the invention. However, it is preferable to represent some species of farm stock (that is, live stock) in view of one of the purposes of this invention being to 75 promote the industry of farming. Moreover, it is preferable to represent grazing or herbivorous animals, since an attractive feature of this device is the lawn adjacent to the farm house which is represented at 11. 80 The lawn which is indicated by the numeral 12 may surround the farm house, as indicated, and the representations of animals may be mentally pictured by the players as intruding upon the lawn. The players may 85 mentally picture themselves as occupants of the farm house 11 vieing or competing with one another in running the greatest number of the intruding animals into the pens 17 formed by the pickets 7 and gates 8 at opposite sides, front and rear of the farm house.

In order to further increase the interest of the players in farm life, an attractive bench or benches 13 may be printed or otherwise pictured on the game-board, and a barn, stable, garage or any other out house or houses may be included in the premises, as indicated at 14.

Although I have described four of the pens, such as shown separately in Fig. 2, it 100 is obvious that a greater or less number of pens may be employed.

The gates 8 may consist of two pickets (similar to the pickets 7) united by a cross bar or strap 8', and the slots in which these 105 gates fit are not numbered, the gates not being numbered, whereas, each of the other slots is numbered, and each of the fence sections 7 is provided with a number which identifies it with the slot having a similar 110 number or identifying characters adjacent thereto. Of course it is understood that iden-

tification characters other than numerals may be employed if desirable.

As a means of storing the pickets 7 and keeping them in a compact and convenient mass, and in such relation that their respective numbers are hidden from view, a storage sheath 15 may be provided as illustrated in Fig. 4, and the internal height of such sheath is less than the length of the pickets 10 7, so that their upper end portions are sufficiently exposed to constitute manipular elements by means of which any one of the pickets may be withdrawn without materially disturbing or disarranging the remaining pickets. It will be seen, therefore, that a player cannot know what number is on the picket being drawn, and having drawn a picket, the player must adhere to his choice, and if this player is unable to properly 20 place the picket as an element of the pen being built by such player, the picket must be returned to the sheath, and the next player may then draw a picket. Of course, the picket which has just been returned should 25 not have had its number disclosed to the other players, so that they cannot gain an advantage by drawing a picket of known identification.

A rule for playing a game with this game 30 device may be substantially as follows:

Assuming that the game apparatus comprises forty-eight counting members 9, forty-eight pickets or fence sections 7, a farm-house and adjacent lawn and four end-35 less series of slots or fence-section-seats 10 and that there are four persons playing the game, each player shall take possession of one pen-site (or endless arrangement of alined slots), placing a gate in the slots 40 which are not numbered. Each player then places four of the counting members 9 in the pen-site to be fenced in by him, and thirty-two of these counting members or representations of animals are placed upon the 45 lawn 12. All of the pickets 7 shall be placed in the sheath or holder 15 so that the numbers thereof cannot be seen, and each player draws one picket at a time from the sheath 15 and places it in the slot 10 (of his pen-site) which is identified with the picket to 50 be placed. If the playing party can place the picket in the formation of his pen, according to number or identification, he is entitled to do so and then take one of the 55 animals from the lawn and place it in his pen, thus gaining an animal. However, when the playing party is unable to properly place a picket by reason of the corresponding identified slot being occupied by another 60 picket, the picket which was last drawn must be returned to the sheath 15, and an animal must be taken from the pen of the playing party and placed on the lawn 12, the playing party thereby losing the count 65 which the animal represents. The player

who first completes his pen by placing a corresponding picket in each slot 10 wins the game and counts to his credit the number of animals or counting members there are in his pen and in the pens of all other 70 other players, but does not count the animals in the center of the board. The playing may progress either rightward or leftward, but preferably, when one player has finished playing, the next player to the right may 75 draw a picket and place or attempt to place the same in constructing his pen. Final counting for the winner may be one hundred or any other desired number.

The directions for two players would be 80 the same as for three or four players, except that each player shall start with six of the counting members in his pen and thirty-six counting members are placed in the center of the board or on the lawn 12. 85

Although I have described this embodiment of my invention very specifically, it is not intended to limit this invention to these exact details of construction and arrangement of parts, but changes may be made 90 within the scope of the inventive ideas as implied and claimed.

I claim:

1. A game comprising a playing field having picket seats inclosing pen-sites, the playing field being provided with indicating characters positioned adjacent the picket seats, the indicating characters of one pen-site having duplicates in the indicating characters of the remaining pen-sites, a plurality 95 of pickets for fitting into the picket seats having indicating characters corresponding to the indicating characters of the playing field, and a receptacle for the pickets concealing the indicating characters thereof, 100 and counters adapted to be placed in the pen-sites as the pickets are placed in the picket seats.

2. In a game-device, a game-board comprising a plurality of series of longitudinally 110 alined sockets arranged to form separate pen-sites, a plurality of game-counting members adapted to be placed on said pen-sites, and a plurality of fence-pickets each adapted to have its lower end fitted into one 115 of said sockets, each of said pickets having thereon an identifying character, each of said slots being provided with an identifying character that is identified with that of one of said fence-pickets and unidentified 120 with other of said fence-pickets.

3. In a game device, a field comprising a plurality of pen-sites each consisting of an endless series of fence-section-seats, a plurality of fence sections each comprising an 125 identifying character and having a manipular portion that presents the same aspect as the corresponding portion of the other fence sections, a storage sheath to hold the fence sections in such relation that their manip- 130

ular portions are exposed and their identifying characters are hidden, and a plurality of counting members adapted to be placed on said pen-sites, each of said fence-sections comprising an identifying character identified with that of one of said fence-sections and unidentified with that of the other

of said fence-sections, each of said fence sections being adapted to be secured in an upright position by a fence-section-seat bearing the same identifying character. 10

In testimony whereof I have hereunto set my hand.

GRACE R. STRONG.
